UNITED STATES PATENT OFFICE.

GEORGE SINCLAIR, OF LEITH, COUNTY OF MID-LOTHIAN, SCOTLAND.

FUEL-FEEDING DEVICE.

SPECIFICATION forming part of Letters Patent No. 288,505, dated November 13, 1883.

Application filed December 26, 1882. (No model.) Patented in England May 19, 1877, No. 2,035, and August 10, 1882, No. 3,808; in France August 21, 1882, No. 138,505; in Belgium August 22, 1882, No. 58,832, and in Germany August 22, 1882, No. 1,629.

To all whom it may concern:

Be it known that I, GEORGE SINCLAIR, residing at Leith, in the county of Mid-Lothian, Scotland, have invented certain new and useful 5 Improvements in Fuel-Feeding Devices, (for which I have obtained the following patents: British, dated May 19, 1877, No. 2,035; British, dated August 10, 1882, No. 3,808; French, dated August 21, 1882, No. 138,505; Belgic, 10 dated August 22, 1882, No. 58,832; and German, dated August 22, 1882, No. S 1,629 V,) of which the following is a specification.

My said invention has for its object to simplify and otherwise improve the construction 15 of a fuel-feeding device, in order to render the same more efficient and suitable for different kinds of coal.

In the accompanying drawings, Figures 1 and 2 are a longitudinal vertical section and 20 an end elevation of a horizontal cylindrical steam-boiler constructed with two internal furnaces, and Figs. 3, 4, and 5 are different views of a compound fire-bar I prefer to use. Each compound fire-bar 6 consists of three 25 pieces, (shown combined and in plan in Fig. 3,) there being two side pieces, 6, having straight outer sides and a middle piece, 7, which is made with lateral inclined projections. Fig. 4 is a side view of the middle 30 piece, 7; and Fig. 5 is a side view of the outer side of one of the side pieces, 6. The inner sides of the pieces 6 are made counterparts of the sides of the middle piece, 7, but so that when the pieces are combined there is a narrow 35 space for the passage upward of air between the middle piece, 7, and the side pieces, 6. My improved compound bar has no external lateral projections which might interfere with the different longitudinal movements of 40 adjacent compound bars, while at the same time each compound bar has within it openings of a zigzag or analogous form, which are believed to be best for the passage of air to the fuel. A double-incline projection, 8, is formed on 45 the under side of the fire-bars, near their inner ends, for the purpose of making them rise and fall a little when their longitudinal movements cause the projection 8 to ride over their inner transverse bearer, 9. Immediately behind the

inner transverse bearer, 9, there is a transverse water-casing, 10, communicating with the boiler at the two sides of the furnace, and the fire-bridge 11 is placed at some distance farther back, leaving a space, 12, into which the more or less consumed fuel descends as it 50 gradually passes beyond the inner end of the fire-bars 6, in consequence of their reciprocating action, combined with the continual addition of fresh fuel at the front or outer end of the furnace. The front ends of the fire-bars 55 6 are supported by and move upon a transverse bearer, 13, the height of which is adjustable by means of screws in the brackets 14, by which it is held. The reciprocating motion is imparted to the fire-bars 6 by connecting-rods 15, jointed to the bars at their inner ends, and at their outer ends jointed upon cranks on a shaft, 16, carried by standard-bearings 17, and driven by means of a spur-wheel and pinion, 18, from a first-motion shaft, 19, having on it a pulley, 20, for a driving-belt, and provided with an engaging and disengaging clutch. Just above the space that the front ends of the fire-bars work through 60 there is fixed an open frame, 21, having immediately above it a plate, 22, on which there is a movable pusher, 23, and this pusher is connected by a pair of adjustable rods, 24, to upright pieces 25, fixed or formed on two of the fire-bar connecting-rods 15. The rods 24 65 are connected to the pusher 23 by a loose connection, so as to allow for the slight angular movement of the said rods. The outer ends of the pusher-rods 24 are also connected to the rods 15 by inclined links 26, and in consequence of these connections the pusher 23 moves backward and forward as the crank-shaft 16 rotates. The hopper 27, in which the coal is put, is made with inclined sides and 70 front, and is fixed directly over the plate 22 and pusher 23, its bottom being open toward the interior of the furnace, and the coals fall from it down upon the plate 22, and are gradually pushed into the furnace by the reciprocating action of the pusher 23. In each hopper 27 there is fixed an iron box, 28, made with a pointed top, to cause the coals to be 75 divided toward each side of it as they descend.

This box 28 is open at its lower inner end, and at its front part it is closed by a movable plate having perforations through which the fireman can see the condition of the fire, while, 5 should it ever be necessary, he can remove the perforated plate and introduce a rod or poker. At the inner side of the open frame 21, which is between the bottom plate, 22, of the hopper and the fire-bars, there is fixed a 10 frame, 29, holding fire-bricks 30, which project into the furnace, and which are made with holes through them, or with channels along their sides, to form passages for the entrance of air. The inner ends of the fire-bricks 30 15 become intensely hot, and the air entering through them is heated and acts in an improved manner in promoting combustion, and in preventing the formation of clinker or the agglomeration of certain kinds of coal. If, with 20 any coals, more air is required than what passes through the fire-bricks 30, the front transverse bearer, 13, of the fire-bars 6 may be lowered a little, to allow air to enter under the fire-bricks 30.

25 I do not desire to claim in this case the particular construction of compound fire-bars above described, as that may form the subject of a separate application.

I am aware that mechanical stokers have heretofore been constructed with reciprocating fire-bars and reciprocating pushers in connection with fuel-hoppers and operating devices. This construction I do not wish to claim, broadly; but

I claim as my invention—

1. The combination of the hopper of a fuel-feeding device, a reciprocating pusher, 23, and fire-bars below the same, with the intermediate frame, 21, frame 29, and fire-bricks 30, having holes or channels through them, substantially 40 as set forth.

2. The combination of feed-hopper, pusher 23, and reciprocating fire-bars, with crank-shaft 16 and rods 15, 24, and 26, and uprights 25, substantially as described.

3. The combination of the hopper and pusher, with frame 21, fire-bars 6, and vertically-adjustable bearer 13, as set forth.

In testimony whereof I have signed my name to this specification in the presence of two sub- 50 scribing witnesses.

GEORGE SINCLAIR.
